UNITED STATES PATENT OFFICE.

PETRUS J. FRANÇOIS, OF QUEBEC, QUEBEC, CANADA.

CUE-TIP.

1,186,177.

Specification of Letters Patent.

Patented June 6, 1916.

Application filed July 16, 1915. Serial No. 40,323.

To all whom it may concern:

Be it known that I, PETRUS J. FRANÇOIS, a citizen of the United States, residing at Quebec, in the Province of Quebec, Dominion of Canada, have invented certain new and useful Improvements in Cue-Tips; and I do hereby declare the following to be a full, clear, and exact description of the invention, such as will enable others skilled in the art to 10 which it appertains to make and use the same.

This invention relates to improvements in tips for pool and billiard cues, the object of the invention being to provide an improved 15 tip of this kind which is made of leather and which is secured in the outer end of the ferrule or tip holder without the use of cement or glue and which is secured so firmly in place that it cannot slip off and will 20 remain on the cue until worn out; and which may be secured to the cue without danger of bending the cue, which may be safely used as soon as it has been placed on the cue, and which may be made and attached at 25 slight cost.

The invention consists in the construction, combination and arrangement of devices hereinafter described and claimed.

In the accompanying drawings:—Figure 30 1 is a sectional view, on a larger scale, of a cue tip constructed in accordance with my invention and showing the same in process of being secured to the outer end of the ferrule or holder. Fig. 2 is a similar view of 35 the same, showing the tip secured in place. Fig. 3 is a detail perspective view of the blank of leather from which the tip is made, a more advanced stage or manufacture. a more advanced stage of manufacture. 40 Fig. 5 is a plan of the same. Fig. 6 is a side elevation of the same. Fig. 7 is a central sectional view of the same.

In the construction of my improved cue tip 1 I first provide a cylindrical leather 45 blank 2 which is cut from thick sole leather. The blank is then cut to form a central stem 3 on its inner side and a flange portion 4 at the inner end of said stem the diameter of which is greater than that of the stem. 50 Thereby an annular shoulder 5 is formed on the inner side of the tip around the stem. The inner portion of the stem and the enlarged flanged portion 4 thereof are then provided with transverse crossed cuts 6, thus 55 dividing the flanged inner portion of the stem into segments 7, which may be turned

inwardly as indicated at Fig. 1, and also as indicated in dotted lines in Fig. 7 to cause the flange segments to aline with the stem 3 and enable the stem to be screwed in a 60 threaded opening 8 in the outer end of the ferrule or tip holder 9 which is made of ivory, brass, celluloid or other suitable material, the said threaded opening 8 provided with an inwardly extending annular shoulder 10 at the outer end of the tip holder as shown. Prior to the insertion of the stem of the tip in the opening 8 and causing the inner end of the stem to project into the outer portion of the tip holder, beyond the 70 inner side of the shoulder 10, a washer 11, which is made of leather, is secured on the outer end of the tip holder by means of screws 12. A small quantity of water is placed in the tip holder to soften the split 75 segmental and diametrically enlarged inner end 4 of the tip stem 3 and the threaded stud 13 at the outer end of the cue stick 14 is then screwed in the tip holder and is provided at its outer end with a substantially 80 conical recess 15. As the stud 13 is screwed home the split diametrically enlarged inner end of the cue stem 3 is engaged in and spread diametrically by the recess 15 thereby forming an integral annular inner flange 85 16 on the inner end of the stem of the tip, which flange 16 firmly engages the inner side of the annular shoulder 10 of the tip holder and is compressed against the same by the stud or stick, as will be understood. 90 A pin 17 is then passed through radial openings 18 in the tip holder and forced through the tip stem as shown in Fig. 2. When the tip stem dries the same hardens, its inner head 16 is permanently expanded, remains 95 permanently in close engagement with the shoulder 10 of the tip holder and hence the tip is so effectually secured to the tip holder that it can never fall off and remains in place until worn.

It will be observed that no glue, cement or other adhesive material of any kind is employed in attaching the tip to the holder in accordance with my invention and hence the permanence of the connection between the 105 tip and the holder is greatly enhanced.

Having thus described my invention, I claim:—

1. A cue, the combination of a tip holder having an inwardly extending annular 110 shoulder at its outer end, a tip having a stem extending into the outer end of the

- shoulder, a washer arranged at the front face of the holder disposed between the tip and holder, the inner end of said stem being split and diametrically enlarged and a stick having a stud, said stud provided in its outer face with a recess, the walls of said recess being inclined from their upper edges toward the center, said stud secured in the tip holder and arranged to engage the stud and compress the split in the enlarged end of the tip stem against the inner side of the annular shoulder, a tip holder, and means through the tip holder and stem for firmly securing the same in position.
- 15 2. A cue comprising the combination of a tip holder having an inwardly extending annular shoulder at its outer end, and provided with oppositely disposed openings, a tip having a stem extending into the outer
- end of the holder, the inner end of said stem being split and diametrically enlarged, and a stick having a stud provided at its outer end, an inwardly extending recess, said stud secured in the tip holder and arranged to engage the stud and compress the split at the enlarged inner end of tip stem against the inner side of the annular shoulder of the tip holder, a washer secured to the front face of the tip holder, and arranged to engage the inner face of the tip, and means through the tip holder and the stem of the tip for holding the same rigid therein.
- 20 25 30

In testimony whereof I affix my signature in presence of two witnesses.

PETRUS J. FRANÇOIS.
